206,126

COMBINED BOOT AND SKI RACK OR SIMILAR ARTICLE

Arden D. Wetterau, 1736 S. Welch Circle, Denver, Colo.

Filed July 15, 1965, Ser. No. 86,163

Term of patent 14 years

(Cl. D33—3)

FIG. 4.

FIG. 5.

6

FIG. 6.

FIGURE 1 is a side elevational view of a combined boot and ski rack or similar article, showing my new design;

I claim:

The ornamental design for a combined boot and ski rack or similar article, as shown.
